(57) **CLAIM**

The ornamental design for a container spout, as shown and described.

DESCRIPTION

FIG. 1 is a front perspective view of a container spout, showing our new design.

FIG. 2 is a left side view of the container spout of FIG. 1, and the right side view being a mirror image.

FIG. 3 is a front view of the container spout of FIG. 1.

FIG. 4 is a rear view of the container spout of FIG. 1.

FIG. 5 is a top plan view of the container spout of FIG. 1; and,

FIG. 6 is a bottom plan view of the container spout of FIG. 1.

The broken line portions of FIGS. 1-6 are included to show unclaimed subject matter only and form no part of the claimed design.
